JOSEPH BANIGAN AND GEORGE W. MILLER, OF SMITHFIELD, RHODE ISLAND.

Letters Patent No. 99,045, dated January 18, 1870.

IMPROVEMENT IN MOULDS FOR VULCANIZING RUBBER PENCIL-TIPS.

The Schedule referred to in these Letters Patent and making part of the same.

To all whom it may concern :

Be it known that we, JOSEPH BANIGAN and GEORGE W. MILLER, both of Smithfield, in the county of Providence, and in the State of Rhode Island, have invented a new and useful improved Mould for Vulcanizing Rubber Pencil-Tips; and we do hereby declare that the following is a full, clear, and exact description thereof, reference being had to the annexed drawings, making part of this specification, in which—

Figure 1 is a plan view, one-half of the puncher-plate being broken away, to show the matrix-plate.

Figure 2 is a vertical section, showing one-half of the matrix-plate, a short distance removed from the puncher-plate, in order to permit the punchers to be pushed through the latter, to facilitate the removal of the finished tips.

The same letters are used, in both figures, to designate identical parts.

This invention relates to a mould for making pencil-tips; and

Our improvement consists in employing, in connection with a matrix-plate and a puncher-plate, a series of punchers, or plungers, reciprocating in the puncher-plate, and so arranged therein, that on the completion of the tips, and the removal of the matrix-plate, said punchers can be made to push the finished tips out of the puncher-plate, after which, they can be readily slipped off the ends of the punchers.

To enable those skilled in the art to make and use our invention, we will proceed to describe its construction and operation.

In the drawings—

A represents the matrix-plate, made of any suitable material, and of convenient size and form. In its upper surface, a series of matrices, *a a*, is formed, the shape or design of which may be largely varied, to suit the taste of the manufacturer. In these matrices, the head of the tip is pressed.

B represents the puncher-plate, in outline like the matrix-plate, but being greatly thicker. Its under surface is to be made to fit neatly upon the upper surface of the matrix-plate; and upon its upper surface it has a ridge or flange, B', of uniform height, and extending entirely around its sides. The height of this ridge is a little more than that of the cylindrical portion of the tips to be formed.

B² B² are a series of vertical holes, formed in the puncher-plate, equal in number to that of the matrices in the matrix-plate, and so arranged that such holes are, respectively, centrally above the respective matrices. These holes are of a uniform diameter from the upper surface of the puncher-plate to a point marked *b*, where they are abruptly contracted to the size of the reduced portion of the punchers. This contraction is

continued a short distance, to the point *b'*, where the hole is again enlarged to such size as it is intended to give to the cylindrical end of the tips, such ends being formed in this part of said holes.

C represent the punchers or plungers, formed as clearly shown in fig. 2, their enlarged portion being made to fit neatly in the upper portion of the holes B'. They are all made of a uniform length, which is to be such, that when their upper ends are flush with the upper surface of the flange B', their lower ends have penetrated through the puncher-plate and entered the matrices, yet not touching the bottom of the latter; and the length of the reduced portion is to be such, at least, as to permit them to be pushed through the puncher-plate a sufficient distance to withdraw the finished tips therefrom.

D represents the rubber tips.

This device may be operated in the following manner:

The punchers having been withdrawn from their plate, the mould is turned upside down, and the matrix-plate removed, the two plates being held together by dowel-pins, or in other convenient manner; after which, a sufficient quantity of raw rubber, in its plastic state, is inserted in the lower enlarged portion of each hole B', entirely filling such portion.

The matrix-plate is then again placed upon the puncher-plate, and the entire mould turned up; after which, the punchers are introduced, and the device placed in a suitable press, which is to press the punchers down to a level with the flange B. It being taken out of the press, the matrix-plate is removed, when the punchers can be pushed through their plate, to withdraw the finished tips, which can then be readily removed from the plungers, without danger of defacing them, and afterward properly vulcanized.

Having thus described our invention,

What we claim, and desire to secure by Letters Patent, is—

1. In combination with a mould for forming pencil-tips, reciprocating punchers or plungers, so arranged as to first form the tips, and then withdraw them from the mould, substantially as and for the purpose set forth.

2. The combination of the puncher-plate, matrix-plate, and reciprocating punchers, constructed and arranged, with reference to one another, substantially as and for the purpose set forth.

The above specification signed by us, this 28th day of December, A. D. 1869.

JOSEPH BANIGAN.
GEORGE W. MILLER.
